(**) Term: **14 Years**

Primary Examiner—Lisa Lichtenstein

(21) Appl. No.: **29/178,526**

(74) Attorney, Agent, or Firm—Brian S. Steinberger; Law Offices of Brian S. Steinberger, P.A.

(22) Filed: **Mar. 27, 2003**

CLAIM

(51) LOC (8) Cl. **23-04**

The ornamental design for a high efficiency air conditioner condenser twisted fan blades and hub, as shown and described.

(52) U.S. Cl. **D23/411**

DESCRIPTION

(58) Field of Search .... **D23/411, 413, D23/370, 378, 379; 416/223 R, 238, 244 R; D12/214; 62/426**

FIG. 1 is a perspective view of a high efficiency air conditioner condenser twisted fan blades and hub.

FIG. 2 is a front side elevation view of the high efficiency air conditioner condenser twisted fan blades and hub of FIG. 1. FIG. 3 is a left side end view of the high efficiency air conditioner condenser twisted fan blades and hub of FIG. 1. FIG. 4 is a right side end view of the high efficiency air conditioner condenser twisted fan blades and hub of FIG. 1. FIG. 5 is a bottom elevation view of the high efficiency air conditioner condenser twisted fan blades and hub of FIG. 1; and,

FIG. 6 is a top elevation view of the high efficiency air conditioner condenser twisted fan blades and hub of FIG. 1.
